UNITED STATES PATENT OFFICE.

ARTHUR DOHmen, OF COLOGNE, GERMANY, ASSIGNOR TO ALBERT F. KRAUSE, OF BUFFALO, NEW YORK.

APPARATUS FOR EFFECTING ELECTROLYSIS.

1,272,397.

Specification of Letters Patent. Patented July 16, 1918.

Application filed December 1, 1914. Serial No. 875,036.

To all whom it may concern:

Be it known that I, ARTHUR DOHmen, a citizen of the German Empire, residing at Cologne, Germany, have invented certain 5 new and useful Improvements in Apparatus for Effecting Electrolysis; and I do hereby declare the following to be a full, clear, and exact description of the invention, such as will enable others skilled in the art to which 10 it appertains to make and use the same, reference being had to the accompanying drawing, and to letters or figures of reference marked thereon, which form a part of this specification.

15 My invention relates to the construction of apparatus for effecting electrolysis, of the type known as "filter-press batteries" customarily used for the production of oxygen and hydrogen by the electrolysis of water; 20 and it has for its object to provide elements that are easily assembled, easily constructed, and more especially are sufficiently rigid to maintain the gas and liquid conduits in register when assembled, as well as to quickly 25 obtain this register during the assembling operation.

The structure is such as to enable me to use pure nickel bi-polar or uni-polar electrodes, which on account of the structure 30 are sufficiently thin, *i. e.*, about one-half mm. to permit of the use of pure nickel, notwithstanding the cost of this metal, but heavier electrodes, such as sheet iron, nickel plated, may be used, as at present.

35 Such a filter-press battery may have as many cells as desired, and in practice such batteries have from one hundred to two hundred cells held together by strong clamping means, the asbestos diaphragms being held 40 in place between adjacent cells. In types now used, by the strong clamping pressure exerted on the cast iron frames. The diaphragms have near their upper edges openings for registering with the gas passages 45 in the frames, and these diaphragms often sag, due to insufficient or uneven pressure, causing the openings to fall out of register with the gas passages causing the gases to mix, they leak electrolyte, due to capillary 50 action, and lose gas through the upper edges.

By the structure herein described and illustrated these disadvantages are overcome.

Referring to the drawings, wherein like parts are similarly designated—

55

Figure 1 is an elevation of a diaphragm and its frame;

Fig. 2 is a section thereof and of an adjacent sheet metal electrode;

Fig. 3 is a vertical section of a modification through the left-hand gas conduit;

Fig. 4 is a like vertical section through the right hand gas conduit;

Fig. 5 is a vertical section through a modification in which the electrodes are supported 60 in a frame, while the diaphragms are clamped between the adjacent electrode frames.

The frames shown in Figs. 1 and 2 each consist of two portions, *a* and *b*, each portion 70 consisting of a rectangular, or other suitably shaped, frame of wrought iron, fiber, or hard rubber. The upper side of the frame *b* is provided with a cut-away portion *d* entirely through the frame at the left hand 75 side. Fig. 1, while the upper side of the frame *a* is provided with a like cut-away portion *c* at the right hand side. The frame *b* has a passage *e* through it which registers with the cut-away portion *c* of frame *a* while 80 the frame *a* has a passage *f* through it, registering with the cut-away portion *d* of frame *b*, that is to say, the two sides are alike in shape, but reversed.

The lower portion of each frame half *a* 85 and *b* is provided with passages *g* for electrolyte or water, arranged to register with one another when the frames are assembled. These passages are oval or elongated, as shown, and are connected with the cell chamber by short narrow slots *h*.

The diaphragm *i* of asbestos or other suitable material is clamped between the two portions *a* and *b* of the frame under pressure, and the portions are then riveted, 95 screwed or otherwise secured together to form a single frame carrying the diaphragm.

Of course it is understood that before placing the two frame portions *a* and *b* in register, a suitable waterproof solution, such 100 as rubber solution, is placed either on the fabric at its edges, or on the frame parts, in order to be sure to destroy the capillarity of the fabric at its edges and prevent the solution from creeping through at the joint. 105

These composite diaphragms are arranged

alternately with metal electrodes *k*, preferably of sheet nickel, which electrodes are provided with perforations *k'* in register with the perforations *e*, *f*, and *g*, in the diaphragm frame, and when placed in position the electrode forms one side wall for a cut-away portion *c* or *d*, and the frame member, *a* or *b* forms the other side wall of the cut-away portion *c* or *d*, so that a chamber is formed between a frame member and an electrode.

Referring to Figs. 3 and 4, I have shown a frame *l*, of wrought iron, hard rubber, or fiber, having around its middle, or only on two opposite frame sides two spaced flanges *m m*, made of any suitable material, for example, nickel-plated iron. Such frames are usually made of four sides with mitered ends, which are welded together by means of a welding torch when made of wrought iron, but when made of fiber or hard rubber they may be connected together in any usual and convenient manner. Each side of the frame *l*, or each of two opposite sides is provided with the spaced flanges *m* and the diaphragm is stretched between the sides of the frame and secured between the spaced flanges *m* by means of rivets; or by simply crimping down or forcing the flanges *m* together.

The frames *l* are provided with water passages *g* and *h*, and gas passages *e* and *f*, as described with reference to Figs. 1 and 2.

In this manner I attain a diaphragm always stretched tight, and supported in such a manner as to prevent any leakage of electrolyte by reason of capillary action, and consequently avoid the extreme care otherwise necessary in packing the joints when assembling the apparatus.

In this case also I use in connection with the diaphragms thin sheet-metal bi-polar electrodes *k* suitably insulated from the frames.

In Fig. 5 I have shown another form. In this form the electrode is supported in a frame similar to that shown in Figs. 3 and 4, and said frame *n* is provided with an electrode *o* composed of one or more layers of metallic screen, for example, nickel-wire screen, preferably but not necessarily of several thicknesses, or of perforated sheets of nickel, clamped or riveted between the spaced flanges *m* in the same manner as the diaphragm in Figs. 3 and 4.

The only difference between this frame *n* and the frame *l* is that there are two gas chambers *d* and *d'* communicating with the passage *f* and two gas chambers *c* and *c'* communicating with the passage *e* one on each side of the electrode. The diaphragm *p* is clamped between adjacent electrode frames *n* in any suitable manner.

By making the frames of wrought iron, rubber, or fiber, I attain a decided advantage

over the cast iron frame customarily in use, the advantage consisting in enabling me to make the frames thinner, thereby decreasing the thickness of the cells and the internal resistance. They are also more yielding, thereby preventing breakage in assembling, and enabling me to make tighter joints and at the same time retain all the advantages of the cells heretofore in use. There is also a considerable decrease in weight, from about 200 lbs. to about 70 lbs.

I claim—

1. In an electrolytic battery of the filter press type, alternate sheet metal electrodes that are both frameless and flangeless, and frames containing diaphragms.

2. A frameless, thin, sheet nickel bi-polar electrode.

3. In an electrolytic apparatus of the filter press type, the combination of a diaphragm frame, parallel flanges within the frame spaced apart, a diaphragm secured between the flanges, and frameless sheet metal electrodes clamped between and alternating with the frames and insulated therefrom.

4. A frameless, sheet nickel bi-polar electrode less than one millimeter in thickness, and diaphragm supporting frames between which said electrodes are clamped.

5. In an electrolytic apparatus of the filter press type, the combination with diaphragm frames, each having a diaphragm mounted therein to divide the interior of the frame into two compartments and having two transverse gas passages through the top thereof, one of said passages being connected with the compartment on one side of the diaphragm by an enlarged, laterally extending chamber and the other of said passages being similarly connected to the other compartment, and electrodes alternating with each frame having holes registering with said passages.

6. A cell member comprising a frame of suitable shape, flanges projecting into the space bounded by said frame, and a diaphragm secured between said flanges, whereby when a number of such members are clamped together the diaphragms and flange members will not be contained between the joints of the members, said member having a gas chamber on each side of the diaphragm communicating with separate gas passages through the member.

7. An electrolytic cell of the filter press type having alternating elements constituting electrode members and diaphragm members, one of said elements constituting a frame; rigid parallel flanges on the frame within the frame opening and contained between the faces of said frame, and a member secured between said flanges.

8. An electrolytic cell of the filter press type having alternating elements constitut-

ing electrode members and diaphragm members, one of said elements constituting a frame, parallel flanges on opposite sides of the frame and rigidly connected thereto

5 within the frame opening and contained between the faces of said frame, and a member whose edges are held in swaged connection between said flanges.

9. In an electrolytic cell of the filter press type, alternating elements constituting electrode members and diaphragm members, one of said elements constituting a frame, paral-

lel flanges within the frame opening, and a member held within said opening between said parallel flanges in crimped connection 15 therewith.

In testimony that I claim the foregoing as my invention, I have signed my name in presence of two subscribing witnesses.

ARTHUR DOHmen.
